DESIGN FOR A WEEDING KNIFE

Erwin Tuller, Beaverton, Oreg.

Application March 15, 1940, Serial No. 90,976

Term of patent 14 years

To all whom it may concern:

Be it known that I, Erwin Tuller, a citizen of the United States, residing at Beaverton, in the county of Washington and State of Oregon, have invented a new, original, and ornamental Design for a Weeding Knife, of which the following is a specification; reference being had to the accompanying drawing, forming a part thereof.

Fig. 1 is a front elevational view of a weeding knife, showing my new design.

Fig. 2 is a side elevation thereof;
Fig. 3 is a top plan view;
Fig. 4 is a bottom plan view; and
Fig. 5 is a horizontal section taken on the line 5—5 of Fig. 2.

I claim:
The ornamental design for a weeding knife, as shown.

ERWIN TULLER.
